DISPLAY COUNTER

Domenico Patriarca, Cranston, R. I.

Application March 22, 1955, Serial No. 35,160

Term of patent 14 years

(Cl. D80—9)

Fig. 1

Fig. 2

Fig. 3

Fig. 1 is a top plan view of a display counter, showing my new design;

Fig. 2 is a side view thereof; and

Fig. 3 is an end elevational view with a portion of the upper right corner broken away.

I claim:

The ornamental design for a display counter, as shown.
